Primary Examiner—Bernard Ansher*Assistant Examiner*—Dominic Simone*Attorney, Agent, or Firm*—Thomas L. Adams[57] CLAIM

The ornamental design for a cosmetic organizer, as shown and described.

DESCRIPTION

FIG. 1 is an axonometric view of a cosmetic organizer showing my new design;

FIG. 2 is a front elevational view thereof;

FIG. 3 is a rear elevational view thereof;

FIG. 4 is a right side elevational view thereof, the left side being a mirror image;

FIG. 5 is a bottom plan view, the organizer in an open position;

FIG. 6 is a top plan view of FIG. 5; and,

FIG. 7 is a top plan view of FIG. 5, the net removed and the lid partially broken away for clarity of illustration.

FIG. 1

FIG. 6

FIG. 2

FIG. 3

FIG. 4

FIG. 5

FIG. 7
